(57) **CLAIM**

The ornamental design for the portable collapsible polygonal stove assembly, as shown and described.

DESCRIPTION

FIG. 1 is a front perspective view of a portable collapsible polygonal stove assembly, showing my design;
FIG. 2 is a rear perspective view thereof;
FIG. 3 is a top view thereof;
FIG. 4 is a bottom view thereof;
FIG. 5 is a rear side view thereof;
FIG. 6 is a left side view thereof;
FIG. 7 is a front view thereof;
FIG. 8 is an exploded perspective view of my design, partially illustrating the collapsible feature; and,
FIG. 9 is an exploded perspective view of my design, illustrating the collapsible feature.
